UNITED STATES PATENT OFFICE.

EDWARD F. KINZLER, OF PITTSBURGH, PENNSYLVANIA, ASSIGNOR OF ONE-HALF TO
ROBERT RAWSTHORNE, JR., OF PITTSBURGH, PENNSYLVANIA.

DEVICE FOR REDUCTION AND ENLARGEMENT CONTROL.

Application filed May 16, 1921. Serial No. 470,157.

To all whom it may concern:

Be it known that I, EDWARD F. KINZLER, a citizen of the United States, and resident of Pittsburgh, in the county of Allegheny and State of Pennsylvania, have invented a new and useful Improvement in Devices for Reduction and Enlargement Control; and I do hereby declare the following to be a full, clear, and exact description thereof.

10 My invention relates to a reduction and enlargement controller.

In photoengraving establishments where all sizes of drawings and copies are received to be rephotographed to certain 15 larger or smaller sizes for process engravings, etc., it has been customary heretofore to obtain the exact reduction or enlargement number by the slide rule and equivalent decimal chart, which is a very tedious and 20 slow operation. Each drawing or copy is marked with the reduction or enlargement number, and after all the numbers have been obtained all the copies or drawings of like number are placed on one large board 25 and can be photographed at one time, as the same adjustment of the camera will do for all having the same reduction or enlargement number.

The object of my invention is to provide 30 a device by means of which the reduction and enlargement numbers may be secured in a few moments, thereby doing away with the slide rule and decimal chart, and all the time and labor occasioned thereby.

35 To these ends my invention comprises the novel features hereinafter set forth and claimed.

In the accompanying drawings Fig. 1 is a 40 plan view of my invention; and Fig. 2 is a fragmentary view of the base plate showing the "setting" edge of the plate.

In the drawing the numeral 2 designates a suitable base-board which may be formed of metal, wood or any other suitable 45 material, having the guide-way 3 formed therein to receive the T-square 4, the connection between said square and said guide being preferably of the ordinary dovetailed type, so that said square is free to be moved 50 readily back and forth in said guide.

The square 4 may be formed of any suitable material, but preferably of some metal which will not rust or corrode, and on which the marks of the scale will stand out 55 clear and defined. Along the arm 4^a of the

square 4 which moves in the guide 3 is the copy-size scale, and in the illustration of my invention there is one row of figures from zero to 12, representing inches and the fractions thereof. Above this line of figures are figures running from zero to 24, designating the inches as before. The arm 5 of the square has the reduction or enlargement size scale, and this scale has, like the copy-size scale, two corresponding sets of 65 like figures.

Pivotal mounted at 6 on the base 2 is the indicator 7 with the arms 8 and 9. The arm 8 is provided with the beveled edge 10 for convenience in adjusting said arm with 70 reference to the sub-divisions of the scales on the square 4.

The base-board 2 is cut away on an angle as at 2^a adjacent the pivotal point 6 to provide a setting edge so that when the indicator arm 8 is in the position shown in the drawing, with the pivotal point 6 in line with the scale line of the copy-size scale, the beveled edge 10 of said arm 8 will coincide with the edge of said cut-away portion, and 80 in this way the adjustment of the indicator is made with ease and accuracy.

The arm 9 of the indicator has the opening 11 formed at its outer end which acts as a window through which the figures representing the reduction and enlargement numbers may be observed. At the opposite ends of the opening 11 are the lines 13 and 14 which are brought into register with the lines indicating the reduction and enlargement numbers, and the neutral position of the arm 9 of the indicator is indicated by the line 15. The lines indicating the reduction and enlargement numbers are supplied with numerals from 1 on up.

Where it is desired to secure the indicator in its adjusted position the board 2 may be provided with the curved T-slot 16 within which the head 17 of the bolt 18 fits. A thumb-nut 19 is provided for tightening up 100 the bolt to retain the indicator in place.

Where the drawing or copy to be reduced in size is, for example, 7 inches in length, and it is desired to reduce it to 5 inches, the square 4 is moved to the right until the line 105 marked 7 in the lower line of the copy-size scale is in line with the pivotal point 6, whereupon the indicator is then moved until the beveled edge 10 of arm 8 coincides with the line marked 5 in the lower line of 110

figures on the arm 5 of the square, as clearly indicated in the drawing. This will bring the arm 9 of the indicator to the position indicated in the drawing, and through the 5 opening 11 it will be observed that the line 14 coincides with the line numbered 105 so that the reduction number for the drawing to be reduced from 7 inches to 5 inches will be 105. The drawing is accordingly marked 10 with the numeral 105.

Suppose, for instance, a drawing 11 $\frac{3}{4}$ inches wide is to be reduced to 5 $\frac{1}{2}$ inches. The square would be moved until the line representing the 11 $\frac{3}{4}$ inches is in line with 15 pivotal point 6, whereupon the arm 8 is moved until its beveled edge 10 touches the outer end of the 5 $\frac{1}{2}$ inch mark on the reduction or enlargement scale, and the arm 9 will have its opening over the number 79 20 of the reduction numbers. If now it is desired to find the height of the reduced drawing, the indicator is retained at the same position, but the square is slid to the size which corresponds to the height of the 25 drawing, say 6 inches, and the indicator arm 8 will give the correct reduced height.

To obtain the enlargement number the same operation is followed, except that instead of moving the arm 8 of the indicator 30 upwardly it is moved downwardly to throw the arm 9 of the indicator over on to the enlargement numbers.

In this manner where there are a number of drawings of all sizes, the reduction number 35 or enlargement number may be obtained in a few seconds, and each drawing has its number applied thereto, so that after all the numbers have been applied the drawings are then classified, the drawings of the 40 same numbers being placed on the same boards to be photographed with one operation of the camera.

While I have described my invention with reference to obtaining the reduction or enlargement numbers of drawings or copies 45 for photoengraved work, it is apparent that the invention may have a wide application for use by any one desiring to know the exact reduction or enlargement number of any 50 article for reproduction or otherwise.

If the subject is over 12 inches it is divided by 2, 3 or 4, according to the desired size wanted, and the same reduction or enlargement number is obtained. For instance,

a 6 inch drawing reduced to 2 inches is just 55 the same reduction number as 12 inches reduced to 4 inches. But by the use of the second row of figures on arm 4^a of the square, drawings up to twenty-four inches may be reduced or enlarged in the same manner as above described. 60

What I claim is:

1. In a device of the character described, the combination of a board having a scale representing reduction and enlargement 65 numbers, a square movably mounted on said board having a copy-size scale on one arm and reduction or enlargement size scale on the other arm, an indicator pivotally mounted on said board adjacent said square, one 70 of the arms of said indicator extending over said scale on said board, and the other over said second-named arm of said square.

2. In a device of the character described, the combination of a board having a scale 75 representing reduction and enlargement numbers, a square movably mounted on said board having a copy-size scale on one arm and reduction or enlargement size scale on the other arm, an indicator pivotally mounted on said board adjacent said square, one 80 of the arms of said indicator extending over said scale on said board and having an opening at its outer end, and the other arm of said indicator extending over said second- 85 named arm of said square.

3. In a device of the character described, the combination of a board having a scale representing reduction and enlargement 90 numbers, a square movably mounted on said board having a copy-size scale on one arm and a reduction or enlargement size scale on the other arm, an indicator pivotally mounted on said board adjacent to the arm of said square, said board being cut away adjacent 95 to said arm of said square to form an angle at its edge, one of the arms of said indicator extending over said scale on said board, and the other arm of said indicator extending over said second-named arm of said square 100 and adapted to coincide with said angular edge of said board.

In testimony whereof, I, the said EDWARD F. KINZLER, have hereunto set my hand.

EDWARD F. KINZLER.
